UNITED STATES PATENT OFFICE

2,486,817

APPARATUS FOR STRETCH FORMING HARD METAL ALLOYS

Richard E. Berger, Hartford County, and Henry P. Hessler, Baltimore, Md., assignors to The Glenn L. Martin Company, Middle River, Md., a corporation of Maryland

Application November 24, 1948, Serial No. 61,802

1 Claim. (Cl. 153—48)

1

This invention relates to sheet metal forming and, more particularly, to an improved apparatus for stretching hard metal alloy sheets into various shapes and forms.

In meeting the present day demand for streamlined structures, such as in the forming of covering material for an airplane, it has been found that the most efficient procedure is to stretch the metal sheets of which such structures are made over die forms in a stretching press. In order to secure an even flow of the metal being formed to the desired shape, it is necessary that some means be provided for coextensive movement between the sheet metal and the stretching die or block used. Adhesion between the surface of the metal sheet and the forming surface causes an uneven flow of the metal worked, producing an unsatisfactory, irregular, wavy surface, finished product. Severe adhesion between the formed sheet and the stretching die may also cause ruptures in the surface of the sheet or damage to the die if great care is not exercised in removing the worked sheet. Various methods for attaining free movement of the metal during the stretching process have been developed which work satisfactorily under certain conditions with various results.

One of these prior methods is to coat the surfaces brought into contact with each other with a lubricant, which method has proved unsatisfactory due to its uncertainty of results and high cost. Another method is that developed by Frank W. Wiesner and Alexander Coulter as described in Patent No. 2,434,379, issued January 13, 1948. The last aforesaid method utilizes the flow characteristics of a rubber sheet placed between the sheet being formed and the stretching block. This method produces satisfactory results in the stretch forming of sheet materials having certain flow characteristics suitable for cold forming, but is not satisfactory for stretch forming sheet materials that have to be worked hot. The working of metal sheets formed from hard alloys, such as magnesium, has raised a number of problems. One of these problems is to provide a method of forming wherein heat in the sheet can be retained sufficiently long to allow for forming. Another problem is to provide means to prevent adhesion between the sheet and the forming means that will withstand the heat involved.

The present invention provides a method whereby a blanket of glass cloth or like heat resistant, hard surface material is positioned over the stretching block of a stretch press to act as a heat-insulating and adhesion-preventing means between a sheet of heated metal and the forming block with the cloth resisting transmission of heat from the metal sheet to the forming block while allowing for movement of the metal rela-

2

tive to said block as the sheet is being formed.

It is among the objects of our invention to provide an apparatus for stretching hard sheet metal to various shapes, including compound curves, whereby provision is made to utilize the free flowing characteristics of the metal to form to the desired shape. The use of a sheet or blanket of glass cloth or like material gives the right degree of sliding action between the stretching block and the held sheet to acquire these results and, at the same time, removes the possibility of the metal sticking to the forming surface. Such sticking of the sheet metal would result in an uneven thickness of the material in the area being formed and a waviness in the surface of the finished product.

Another object is to provide an apparatus for stretching hard alloy sheets while hot.

Another object is to provide an apparatus for stretching metal that eliminates the necessity of coating each part with a lubricant.

Still another object is to provide a method where sheet metal is heated immediately prior to being formed and is then formed over cold forming dies. The use of a heat insulating blanket placed adjacent the forming die eliminates the need for installing costly heating means in or around the press as has been formerly considered necessary in the forming of certain alloy sheet materials.

A further object is to provide for the stretching of hard metal sheets that reduces the spoilage and waste formerly incurred in finishing materials in accordance with the known art. The clean, uniform condition of sheets produced by the method of our invention eliminates waste due to defective surfaces which formerly resulted from the non-uniform application of a lubricant or the too rapid dissipation of heat.

Further objects, advantages, and novel features of our invention will be apparent from the following description in which reference is made to the accompanying drawing wherein like numbers refer to like parts.

Figure 1 is a perspective view of the stretching block covered by the stretch blanket of this invention partially fragmentated to show its position relative to the bottom of the stretching block.

Figure 2 is a partial end view of a stretching press embodying our invention with an electrically heated oven positioned adjacent thereto.

Referring more specifically to the drawing, we have illustrated in Figure 1 a sheet or blanket of glass cloth 10 or like heat resistant hard surface material having stretch and friction characteristics placed over a form die or stretching block 11 of a conventional stretching press with the blanket dimensioned so as to exceed the forming surface of the stretching block. The stretch-

ing block 11 is supported by a platform 13, as illustrated in Figure 2, arranged to be actuated and forced upwardly by a hydraulic plunger 14. A heated sheet of metal 15 to be formed is secured in the stretching press at opposed edges 12 held by jaws 16 operated by hydraulically actuated clamps 17 supported by a base 18. Sufficient slack is allowed in the central portion of the sheet 15 for shaping it to the desired form. During the operation of forming sheet 15, the stretching block 11 with the glass cloth blanket 10 laid smoothly over its forming surface is forced in an upward direction against the inside surface of the sheet by means of the hydraulic plunger 14 acting against the stretching block supporting table 13. The forcing of the table 13 upward presses the stretching block 11 covered by the glass cloth blanket 10 against the formable sheet 15, shaping it to conform to the shape of the stretching block 11. The sheet metal to be formed may be of any strong ductile material, such as steel, aluminum, magnesium, or their alloys. Prior to forming, the sheet 15 is heated sufficiently in a suitable oven to provide the necessary ductility. This may be accomplished by means of any of the different types of heating devices known in the metal working art. However, we have found that a conventional type of oven heated by means of electric strip heaters, or the like, is suitable for use when located near a forming press used for forming hard alloy metal sheets of standard thicknesses. Such an oven 19 is illustrated in Figure 2 as positioned on a suitable support means 20 placed adjacent the press.

In stretch forming according to the method of our invention, the procedure is as follows: A quantity of sheets of metal to be formed is inserted in the oven in stacked formation as at 25. The temperature to which the stack 25 is to be heated will depend on the forming characteristics of the metal. For example, in the forming of magnesium alloy sheets of conventional thicknesses, a temperature range of from 550° to 650° F. has been found suitable. Heating the oven 19 is provided for by a top heating unit 21 connected to a suitable source of electric energy by wires 22, and the bottom unit 23 is likewise energized through leads 24. The top unit 21 is held in place by suitable side members 26 attached to the inside walls of the oven 19. A sheet 15 is removed from the stack 25 in the oven when sufficiently heated for forming and placed in the stretch press with opposed edges 12 gripped by jaws 16; and the pressing block 11 covered by blanket 10 is forced against the area to be formed causing the metal to flow evenly to the shape of the block which may consist of any number of complex shapes, such as the compound curved form illustrated in Figure 1.

The hard surface of blanket 10 has a low coefficient of friction that allows for a uniform sliding movement between not only the stretching block and the underside of the blanket, but also the blanket and the sheet being formed. The sliding movement of the metal sheet 15 over the insulating blanket 10 placed adjacent the stretching block facilitates the forming of the metal by preventing any tendency that the metal would otherwise have to adhere to the stretching block. This freedom of movement allowed the metal being formed results in the elimination of any unevenness which might otherwise develop in the finished product. The heat insulating qualities of the blanket 10 are such as to act as a heat

5 barrier and to sufficiently retard transfer and loss of heat from the metal sheet 15 as to allow for hot forming of the sheet to the desired shape. Upon the completion of the stretching operation, 10 pressure against table 13 is released, allowing the stretching block 11 to drop freely away from the formable sheet 15 in its then formed condition. Separation of the forming block 11 from the formed metal sheet 15 is readily accomplished as the glass cloth blanket 10 prevents any adhesion between these parts leaving the surface of said formed sheet in a smooth, clean condition ready for the next operation without need for degreasing or further conditioning.

15 Any compression-resistant, hard surfaced, low coefficient of friction material may be used. It has been found that a fabric woven of threads of such material has the necessary flexibility to fulfill the requirements of element 10. Glass cloth fabric woven from a continuous filament fiber, known in the trade as the electric grade of cloth, has been found to be well suited for the purpose. This type of material not only has an unusually high tensile strength, which resists tearing of the blanket, but also provides an extremely durable hard surface finish which greatly facilitates the desired sliding action between the sheet and forming block so as to prolong the service life of the blanket. The low cost and long life of the material used in the method of our invention as compared with the prior art methods are marked and important features from a large scale production standpoint.

20 We are aware that prior to our invention, other forming machines have been made with sheet holding devices; therefore, the machine is shown and described for illustrative purposes only. It is also to be appreciated that certain changes, alterations, modifications, and substitutions can 25 be made without departing from the spirit and scope of the claim.

30 We claim as our invention:
 35 A machine for forming a hot metal sheet comprising a movable stretching block having a forming surface, a heat insulating blanket of glass cloth arranged between the forming surface of said stretching block and a sheet of metal to be formed, said heat insulating blanket being unrestrained at the edges and proportioned to exceed the area of the forming surface of the stretching block so as to provide a heat barrier adapted to retard transfer of heat from the hot metal sheet to the stretching block responsive to forming movement of the said block, means fixed 40 with respect to said block to hold said metal sheet by its edges free of the stretching block, and means for moving the block to apply forming pressure against said restrained sheet of metal.
